COMBINATION TOOLHOLDER HEAD

Charles L. Waite, Dorchester, and Charles F. Waite, Cambridge, Mass.; said Charles L. Waite assignor to said Charles F. Waite

Application January 18, 1947, Serial No. 722,864

1 Claim. (Cl. 77—58)

1

Our present invention is a novel and improved tool-holder comprising a head to be attached to the rotating shaft or spindle and to provide for automatic precision feeding, for a grinding, boring, or cutting tool for boring, facing, or finishing work.

An important feature of our present invention is that the tool-holder head can be instantly changed from a fixed grinding, cutting, or facing operation into an adjustable feed for the tool fitted within the head while the tool-holder and its attached spindle are in rotation.

Also our combination tool-holder head, while primarily intended to be attached to and rotated with a spindle, can be fitted for grinding, boring, or facing on work that is either held stationary or with the work itself revolving.

A further feature consists in the advantage of having the tool-holding element interchangeably fitted in the head to be of any desired length for the feeding capacity of the work desired. Also, interchangeable tools can be readily fitted to and removed from our combination tool-holder head and a quick manual adjustment effected to position the tool relatively with the work and, thereupon, the desired operation commenced and the automatic feed can be thrown into actuation at any time.

A further feature consists in the arrangement and detachment of a grinding wheel or tool with a separate motor to rotate the grinding wheel, and the motor and grinder being belt-actuated, permits the grinder to follow an eccentric grinding path with the belt tight at any time.

For this purpose we provide an adjustable link and means to slide the motor on a suitable carrier as the grinding wheel follows its rotative path on the work. Also, the grinder could be centered, if desired, with the spindle on which the tool-head is mounted. Our invention thus enables a standard type of machine with the rotating spindle, such as a milling machine, to be equipped to do grinding, boring, or facing work with an automatic feed on the operating tool.

A further important feature is the novel and improved method of actuating the automatic feed by having a toothed star wheel intermittently rotated by striking against a fixed abutment, so constructed and arranged as to secure a smooth, even, and straight full line contact between the fixed tooth and the star wheel teeth.

Other novel features, combinations, and important advantages will be hereinafter more fully pointed out and claimed.

2

Referring to the drawings illustrating preferred embodiments of our present invention:

Fig. 1 is a plan view of our combination tool-head equipped with the grinding wheel and an actuating motor to rotate the grinding wheel independently of the rotation of the spindle on which the tool-holder head is mounted;

Fig. 2 is a side view of the apparatus as shown in Fig. 1;

Fig. 3 is an enlarged plan view of our combination tool-holder and automatic feed shown mounted on a rotating spindle;

Fig. 4 is a side view;

Fig. 5 is a detailed view illustrating the full line contact between the star wheel teeth and the fixed tooth or abutment imparting a rotative movement and, hence, automatic feeding of the tool-carrying rod;

Fig. 6 is a further detailed view illustrating a full line separating operation between the star wheel teeth and the fixed abutment;

Fig. 7 is an enlarged detail partly in cross-section illustrating the shaft to hold the grinding wheel;

Fig. 8 is illustrative of a modified form of construction wherein the tool head and arrangement of the abutment for automatic feeding actuation are in separate elements;

Fig. 9 is a cross-sectional view on the line 9—9 of Fig. 8, and

Fig. 10 is an end view looking from the right of Figs. 3 and 4.

Fig. 11 is a fragmentary side view illustrating a modified form of movable motor mounting.

Referring to the drawings, and particularly Figs. 4, 5, and 6, our combination tool-holder head comprises a block 1 having a cylindrically bored opening therethru as indicated in dotted lines at 2, with a keyway 3, said head being formed on a tailstock 5 for attachment to a rotating spindle. The tailstock 5 has a bearing shown in dotted lines at 6, Fig. 3, adjacent the tool head to receive a block 10 having a corresponding bored opening to fit on the bearing 6. A ring 7 secured to the surface of the bearing by a set screw 8 holds the block 10 in rotatable position between the ring 7 and the rear face of the block 1. At one end of the block 10 is fitted the adjustable abutment or tooth to be moved into and out of contacting position with the teeth on the star wheel to actuate the feeding movement, to be described. This adjustable tooth 12 is formed with a cylindrical body portion 14 fitted within a correspondingly bored opening indicated in dotted lines at 15 and slidable in said bore into

45 and out of operation position.

For this purpose we provide a slot 16, see Fig. 3, to receive the shank 17 having a threaded stem 18 fitting in a correspondingly tapped opening in the cylindrical part 14 and actuated by a milled nut 20 projecting above the top surface 21 of the block 10 and of sufficient area to span the slot 16. Thus, the nut 20 serves to slide the tooth 12 into and out of operative engagement desired and also with a slight twisting of the knurled nut 20, the tooth 12 will be locked where adjusted either in operative or inoperative position.

At the opposite end of the block 10, we provide a bored socket 22 and a threaded cross-opening at right angles to said socket, as indicated at 23, to fit a rod or other device in the same to hold the block 10 against rotation on the bearing 6 when the tailstock is attached to a rotating spindle and the tool holder is being rotated. A second bored opening 24 is fitted, as shown, to be simply attached to a fixed bracket, if desired.

Adapted to slide in the cylindrical opening 2 in the block 1 is a tool-holding cylinder 25 having one end portion threaded as indicated at 26, and with tool-holding sockets, herein shown as two in number, 27 and 28, in which a cutting or milling tool 30 may be fitted. In the socket 27, the inner portion or shank of a tool 30 may be of suitable size and cross-section to fit snugly therein, and same is held in position by a set screw 31 fitted in the tapped recess 32 in the axle end of the tool-holder 25, as best shown in Fig. 3. Thus the tool 30 is fitted and locked and is readily removed and replaced in the cylindrical holder 25.

In the second tool-holding recess 28, I prefer to fit a flanged bearing 35 with the flange extending upwardly and thru a U-shaped opening in the face of the block 1 extending from approximately the dotted line position 36 to the opposite edge 37. This flanged tube 35 is adapted to slide in the U-shaped opening in the face of the plug 1 and is diametrically opposite the key 40 adapted to slide in the keyway 3, shown in dotted lines in Fig. 3.

Thus the cylindrical tool-holder 25 is slidingly fitted in the block 1 of our combination tool-holder head, with a strong and rigid bracing construction. The tube 35 can be utilized to also receive the shank of a tool and same would be held in position by a relatively long set screw fitted in the end 32 of the cylindrical tool-holder 25, the bored opening 32 extending thru the walls of the tube to impinge against the shank of the tool held therein. Thus, the flanged tube 35 constitutes a tool-holding element and a bracing element for the longitudinal movement of the cylindrical tool-holder 25 and also as a stop against the travel of the cylinder in one direction, viz., to the limit of the U-shaped slot 38, shown in dotted lines, Fig. 4.

We also provide means to lock the tool-holder 25 in the block 1, if desired, by forming a flattened surface as shown in dotted lines, Fig. 1, at 41, which is engaged by a socket-headed set screw 42 threaded thru a correspondingly tapped opening in the side of the block 1 in alignment with the flattened surface 41. The inner end of this socket set screw 42 may also constitute a stop in co-operation with the length of the flattened surface 41 to limit the lengthwise adjustment and, hence, the feeding movement of the tool holder 25 relatively with the block.

Mounted on the threaded portion 26 of the cylindrical tool-holder 25, we provide a star wheel 50 with a bevelled face 51 carrying indications

thereon for adjustment, see Fig. 3, the outer face of the star wheel having a series of teeth 52 and the inner face constituting a bearing against the end wall 54 of the block 1.

To hold the star wheel 50 in bearing and thrusting engagement with the face 54, we provide a pair of dove-tailed semi-sectional washers 55—55 constituting thrust plates attached to a face 54 of the block 1 by counter-sunk screws 56—56, see Fig. 4, the undercut face of the washers 55 being in a sliding fit with the bevel 51, see Fig. 6. This star wheel 50 has a plurality of teeth, here shown as ten in number, which project into the path of engagement with the abutment 12 when the same is moved in outermost or operative position, viz., to the right viewing Figs. 4, 5 and 6. Thus, with the tailstock 5 secured to the rotating spindle, and the block 10 held rigidly against rotation on the tailstock, the block 1 carrying the cylindrical tool-holder 25 and tool 30 will be rotated at the speed of rotation of the tailstock and spindle; hence, the teeth 52 on the star wheel 50 will strike the abutment 12 and be rotated one tooth for each revolution, thus feeding forwardly the tool-holder 25 the distance which the star wheel 50 travels on the threaded portion 26 for the space of the movement of one tooth.

These teeth 52 are formed on a bevel in the star wheel 50 and, accordingly, we so construct, position, and arrange the fixed tooth or abutment 12 to strike these teeth 52 so as to give a full line contact both during the time of contact between the two teeth as they roll in contact with each other, and a full line contact at the conclusion of said movement when the teeth are separated.

For this purpose the tooth 12 is set on an angle relatively with the axis of rotation of the star wheel 50 and has its contacting face bevelled to cooperate with the bevel of the teeth 52.

In the operation of the apparatus as thus described, a suitable tool 39 is fitted in the socket 27 and the set screw 31 tightened. The abutment 12 is kept retracted or is retracted by manipulation of the thumb nut 20 and the star wheel 50 is rotated by hand until the tool 30 is in approximate desired position to operate on the work. Thereupon the thumb nut 20 is moved to slide the abutment 12 into the path of the teeth 52 of the star wheel 50 and the power turned on for rotation of the spindle to which the tailstock 5 is attached. As the block 1 rotates, the tool 30 will be swung around the circular arc to which it has been adjusted and will be fed forwardly step-by-step into the work by the intermittent action of the star wheel 50 by its successive teeth 52 striking against the abutment 12 until the work is completed.

Where a short boring or facing operation is desired, the tool can be fitted in the tube 35 and the same operation repeated. Meanwhile, the block 10 will be held against rotative movement by any suitable attachment secured to the same thru the bored recesses 22, 23, or 24 and attached to some fixed part of the worktable, bench, or machine.

Referring to the separately rotating grinder wheel attachment, as illustrated in Figs. 1, 2, and 7, we attach to the block 10 by socket set screws thru the bored openings 23 and 24, a bracket 60 formed at one end of a plate 61, carrying a pair of dovetailed slides 62—62 in which a sliding plate 64 may travel, this plate carrying a motor designated generally at 65. On one end of the projecting armature shaft 66 of the motor, we

attach a pulley 67 around which a V-shaped belt 68 is led, which, in turn, is led around a pulley 70 mounted to rotate freely on a bearing 71 carried by a shaft 72. This shaft would project into the head 1, being fitted, for example, in the flanged tube 35 on the cylindrical tool holder 25 and would be retained in position thru a set screw or the like in a depression 74 in the end of the shaft 72.

Thus, the pulley 70 would be loosely rotating on the bearing 71 while the shaft 72 would be in fixed position and would be acted upon to be fed forwardly by the action of the star wheel and abutment 12. The shaft 72 has reduced bearings formed thereon, see Fig. 7, to carry ballbearing raceways 74' and 76 assembled within a rotatable circular housing or casing 77, being held, respectively, in position by a nut 78 at one end threaded around a reduced portion of the shaft adjacent the raceway 76, and by a ring nut 79 at the other end threaded into an inner circular threaded opening near the open end of the circular casing 77. The casing has an outstanding flange 80 which may be secured to a corresponding circular flange 81 on the pulley 70.

A plurality of set screws 82 arranged peripherally around these flanges unite same. The reduced sections of the shafts 72 are indicated at 83 and 84, and a ring spacer 85 is fitted between the ballbearing raceways as clearly shown in Fig. 7, thus giving a firm bearing and leverage. The bearing 74' would normally have its lower ring contacting directly onto the reduced portion 84 of said shaft; and we prefer to supply a bushing 86' for the inner raceway 85, which bushing has a rim 87 to hold the bearing firmly between the said rim and the nut 78 without binding on the other raceway 84. The casing 77 is formed, preferably, as an integral part with an extending shaft 90, which carries the grinding wheel 91 on its outer end, being threaded or otherwise united thereto in any suitable manner as by a hub threaded into the correspondingly threaded end 92 of the shaft portion 90 and locked by a nut 94 on the outer end, thus binding the grinder 91 in rigid rotation with the shaft 90.

In order to hold the belt 68 in driving relation between the pulley 67 on the motor and the pulley 70 on the grinder shaft 90 while the grinder follows its circular arc or path upon the work, we provide a rigid adjustable belt tightener, comprising telescoping arms 95 and 96 interlocking in the intermediate portions and being bound in adjusted position by a nut 97 on a bolt 98 passing thru slots 99—99 in each of the overlapping portions of the arms 95 and 96, see Figs. 1 and 2.

The end of the arm 96 has a hole of suitable diameter to envelope the shaft 66, and the opposite end of the arm 95 has a corresponding hole to enable the arm to encircle the shaft 72. Thus, as the grinder is actuated in its arc, the entire motor 65 may be slid to and fro on the plate 64 in the guide 62 by this rigid link construction and simultaneously keep the belt 68 tight and the grinder rotating.

Referring to Figs. 8 and 9, a modified form is shown wherein the tool head 1, with its tool-holder and feeding star wheel and connected parts, is formed separately from the block carrying the abutment 12, which latter may be spaced a considerable distance from the head 1 in order to relieve weight on the supporting shaft. For this purpose, we would make the abutment 12 on a shank of considerable length and would mount the block 100 between collars 101 and 102 on the

shaft 103. Preferably the collar 101 would be provided with a hollow hub 105 on which the block 100 would fit. The lower part of the block 100 is fitted with a lug 106, to which is attached 5 a brace or bracket 107 by a bolt 108 or a pair of bolts, as indicated in Fig. 8, the bracket extending to the fixed part of the machine or worktable so as to hold the block 100 in non-rotative position on the shaft 103. The abutment 12 may be moved into and out of operative position by the thumb nut 120 and the entire operation is identical to that already described, but it enables us to make two attachments spaced from the end of the shaft which supports both, as will be readily appreciated.

Referring to Fig. 11 illustrating a modified form of movable mounting for the motor 65 and the rigid link connection to hold the belt 68 under desired tension while the grinder follows its or-

20 bital path, we mount the motor 65 on a pivotal, rocking, or hinged construction. For this purpose we may provide a typical hinge comprising one leaf 123 which is secured to the support 61, and a second leaf 124 attached to one of the motor 25 supports, the two leaves being adapted to rock on a pivot pin 125.

Thus the motor 65 may rock back and forth on the pivot 125 while the belt 68 and rigid adjustable link elements 95 and 96 hold the belt 30 68 under tension and drive the grinder 91 during its orbital path. This modified form of construction is also important as utilizing the weight of the motor 65 bearing against the belt 68 during the adjustment of the link elements 95 and 96. 35 Also, this hinge construction or an equivalent swinging movable actuation eliminates the danger of filings, dust, or dirt getting into the slide 62 in the form shown in Fig. 2.

It is also important that the axis of the pulley 40 67 be considered as the central point for attachment of both the link elements and the belt, the same being herein shown as the shaft of the motor 66, but in case a gear reduction is employed between the motor and the driving belt 67, the 45 axis of the pulley is necessarily concentric in the attachment of both the adjustable link elements 95 and 96 as well as the belt 68, as will be readily appreciated.

We claim:

50 A combination tool head of the kind described having a sliding tool-holding element adapted to traverse said tool-head within fixed limits, a rotatable member on said slide to effect the sliding movement relatively with the tool head, said rotatable member being held in assembled position by a pair of dovetailed semi-sectional thrust plates removably secured to the head.
